The ornamental design for a memory card reader, as shown and described.

DESCRIPTION

FIG. 1 is a front perspective view of a memory card reader showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof; and,

FIG. 9 is another perspective view thereof with unclaimed memory card.

The evenly dashed broken lines in the figures depict environmental subject matter and form no part of the claimed design.
